UNITED STATES PATENT OFFICE

94,642

DESIGN FOR A SERVING TRAY

Blanche S. Van Dusen, Excelsior, Minn.

Application December 7, 1934, Serial No. 54,341

Term of patent 14 years

To all whom it may concern:

Be it known that I, Blanche S. Van Dusen, a citizen of the United States, residing at Excelsior, in the county of Hennepin and State of Minnesota, have invented a new, original, and ornamental Design for a Serving Tray, of which the following is a specification, reference being had to the accompanying drawing, forming part thereof.

In the drawing,

Fig. 1 is a plan view of the serving tray showing my design;

Fig. 2 is a longitudinal cross-section of the same on the line 2—2 in Fig. 1; and

Fig. 3 is a transverse cross-section on the line 3—3 in Fig. 1.

I claim:

The design for a serving tray substantially as shown and described.

BLANCHE S. VAN DUSEN.
